Fig. 1.

This figure shows a 3D perspective view of a curved track assembly. The assembly is built on a rectangular base 10. The top surface of the base is labeled 12. The track itself is a curved structure with a top surface labeled 12. The inner curve of the track is labeled 98. The outer curve of the track is labeled 92. The track is supported by a series of curved supports labeled 94. The track has a hatched pattern on its inner surface. There are several labels with numbers: 18, 24, 96, 102, 100, 106, 44, 70, 26, 96, 18, 16, 90, 78, 10, 12, 98, 92, 94, 62, 40, 18, 96, 92, 94, 83, and 100. There are also two small cylindrical components labeled 78 and 83.

DISHWASHER

Paul M. Seiple, Redmond, Wash.

Application July 20, 1942, Serial No. 451,578

2 Claims. (Cl. 141—9)

My invention relates to improvements in dish washers and pertains particularly to the rotary cage type, adapted to wash and rinse dishes and the like.

In the accompanying drawings:

Figure 1 is a perspective view of a dish-washer in accordance with my invention illustrating the cover parts of the cabinet in open positions;

Figure 2 is a vertical sectional view;

Figure 3 is a top view with the covers removed, with a portion of the structure broken away;

Figure 4 is a horizontal sectional view;

Figure 5 is a bottom view of a container basket; and

Figure 6 is a top view of a multiple device.

In the embodiment of the invention selected for illustration, I make use of a cabinet 10, as in Figure 1, made up of four side walls 12 arranged to provide an enclosure square in cross section, as when viewed in Figures 3 and 4. The walls 12 are of equal length and support a bottom 14 spaced a short distance inwardly from the lower ends of the walls. All the walls and the bottom are preferably formed of wood.

Inside the cabinet 10 is arranged a metallic, earthenware or plastic liner 16, as in Figure 2, circular in cross section, to moistureproof the cabinet 10. While the liner 16 has four points of contact with the walls 12, additional support is afforded by diagonal wooden strips 18 arranged at forty-five degree angles to the engaging walls and located at the upper end of the liner. This liner has a flat bottom 20 resting on the bottom 14, with the upper end of the liner terminating substantially flush with the upper ends of the walls 12. An annular flange 22 is carried by the liner 16 a short distance inwardly of its upper end.

Inside the liner 16 is mounted a rotary cage or receptacle 24 for containing dishes and the like to be washed. This cage includes a wall 28 circular in cross section and a bottom 30. Both the side wall and the bottom are formed of wire mesh, with the mesh of the bottom slightly larger than in the wall to facilitate passage of solids washed from the dishes.

The bottom 30 of the cage rests on a supporting structure 32 extending upwardly inside the cage and connected with a top supporting structure 34. The supporting structure 32 comprises two especially treated wood bars 36 crossed in right angular relationship and interfitting at 38 so as to lie in a common plane. Four upright bars 40 are secured to the outer ends of the bars 36. Recesses 42 are formed in the upper faces of the

arms 36 for receiving the lower ends of the bars 40. Slots are cut in the bottom 30 to accommodate the bars 40. Two of the bars 40 are arranged edgewise to the wall 28 in a common plane and the remaining bars are arranged flatwise against the wall.

The upper supporting structure 34 also comprises right angularly crossed arms 44 interfitting at 46 to lie in a common plane and recessed at 48 to receive the upper ends of three of the bars 40. The outer ends of the bars 44 fit inside the wall 28, as in Figure 3.

Upon the wall 20 is mounted a body 50 provided with a recess 52 for receiving a convexed bearing 54 conforming to the shape of the recess. This bearing is provided with a flange 56, as in Figure 5, secured to the bars 36 by screws 58.

A short shaft 62 is provided with arms 64 fixedly secured to one of the bars 44 by screws 66. An opening 68 is provided in the bars 44 through which the shaft 62 is extended for pivotal connection at 70 with a crank 72 through the medium of which the cage is rotated relatively to the cabinet. This crank is provided with a knob 74 to facilitate manual rotation of the cage. To the two bars 40 lying facewise against the wall 28 are attached two agitators 76 arranged at an angle of about forty-five degrees to their respective bars 40. Both agitators 76 comprise especially treated wood or plastic members having their upper and lower ends fitting in recesses in the top and bottom supports 34 and 32, respectively.

A water inlet pipe 78 extends through one wall 35 of the cabinet 10 and has communication with the liner 16. This pipe is located a short distance beneath the upper end of the liner and slightly above an overflow pipe 80 communicating with the liner and the cabinet 10 in one corner thereof, through the bottom 14 for connection with a T 82 coupled to an outlet pipe 83. The T 82 extends through the bottoms 14 and 20 and is normally closed by a convexed body 84 attached to a carrier 86 hingedly connected at 88 with bottom 20.

To the carrier 86 is connected one end of a rod 90 extending upwardly inside the liner 16, through an opening in the annular flange 22 and through slots 92 in cover sections 94 hingedly connected at 96 with the upper ends of two of the walls 12.

To the inner face of each cover section 94 is attached a rib 98, as in Figure 1, the two ribs providing an annular rib when the cover sections are closed to bear on the annular flange 22 and

provide a watertight seal. A slot 100 is formed in each cover section to provide accommodation for the crank 72. The cover sections are also provided with flanges 102 having overlapping engagement in the closed positions of the cover sections.

One of the bars 44 extends only from the other cross bar 44 to the peripheral wall of the cage 24, as in Figures 1 and 3. This provides a large opening in the upper end of the cage to facilitate loading and removal of the articles. The greater part of the washer is formed of especially treated wood or plastic so as to require a relatively small amount of metal.

In operation, the liner 16 is filled with water up to the inlet of the overflow pipe 80. Rotation of the cage imparts an efficient washing agitation to the liquid by reason of the arrangement of the two agitators 76 and the two bars 40 arranged edgewise to the cage. All the liquid may be drained from the washer by lifting the valve rod 90.

Figure 6 illustrates a washer in which two cabinets 104 are connected as a unit, both of which correspond to the washer structure of Figures 1 through 3.

The crank 72 and the shaft 62 are provided with aligned openings for the reception of a removable pin 106 which locks the parts in rigid relationship to provide a fixed connection between the crank and the shaft and prevent wobbling of the cage.

While I have illustrated the perfected form of

my invention, it is to be understood that the foregoing description is for illustrative purposes only, and I do not desire to be limited by any of the details shown or described, except as defined in the appended claims.

I claim:

1. A rotary cage for a dishwasher, comprising a cylindrical body having perforated side and bottom walls, a reinforcing structure for said cage including two pairs of diametrically opposed flat slat-like members arranged vertically within the body, the members of one pair extending radially with their outer edges in engagement with the perforated side wall, the other diametrically opposed slat-like members arranged with their flat faces against the perforated side wall centrally between the members of the first pair, and agitators carried by said reinforcing structure inwardly of the two opposed members having their flat faces against the side wall, and said agitators arranged in close angular relation to said last members.

2. A rotary cage for a dishwasher such as claimed in claim 1, wherein the reinforcing structure also comprises top and bottom bars, the bottom bars being arranged in cross relation and secured to the bottom wall of the cage, the top bars being arranged in crossed relation and secured within the upper end of the cage, and the top and bottom bars being provided with recesses within which the ends of the vertical members and agitators are secured.

PAUL M. SEIPLE.
